Inventor,
William T. Rose, by
G. Kennedy,
Attorney.

UNITED STATES PATENT OFFICE.

WILLIAM T. ROSE, OF WATERLOO, IOWA.

POWER-ACTUATED HAIR-CLIPPER.

1,368,354.

Specification of Letters Patent. Patented Feb. 15, 1921.

Application filed May 29, 1919. Serial No. 300,573.

To all whom it may concern:

Be it known that I, WILLIAM T. ROSE, a citizen of the United States of America, and a resident of Waterloo, Blackhawk county, 5 Iowa, have invented certain new and useful Improvements in Power-Actuated Hair-Clippers, of which the following is a specification.

My invention relates to improvements in 10 power-actuated hair-cutters, and the object of my improvement is to supply for the use of barbers and other persons a device of this class, comprising power transmission mechanism of a simplified, convenient kind, having few parts, light, compact and easily assembled or disassembled.

This object I have accomplished by the means which are hereinafter described and claimed, and which are illustrated in the accompanying drawings, in which Figure 1 is 20 a plan of the under part of my improved power-actuated hair cutter with parts removed or broken away, and Fig. 2 is a detail perspective view of the means employed in 25 said device for reciprocating the movable cutter member.

In said drawings, similar numerals of reference denote corresponding parts throughout the several views.

30 The hair cutting device shown is of a well known type, having a pair of coacting dentated cutting members or plates 6 and 8, of which the plate 6 is detachably fixed upon a shank or body 2 by screws 16, said body 35 being integral with an elongated handle 1, the other cutting plate 8 being mounted to be reciprocated across the plate 6.

The cutter 8 is positioned between said fixed cutter 6 and a removable cap-piece 12 40 opposite, said cap-piece being secured to said body 2 by a flat-headed screw 11 having thereon a wing-nut not shown, engaging the outer face of the cap. The cutter-plate 8 has rectangular openings 9 to receive smaller 45 rectangular studs 7 on the plate 6 slidably to limit its scope of movement or reciprocation, and also has a rectangular recess 10 medially located in its inner transverse edge.

The means for reciprocating the cutter- 50 plate 8 are housed in a small oblong boxing 4 having two spaced transverse partitions 22 and 25 and a terminal wall 34, said partitions and wall having medially-located longitudinally-alined circular orifices or bearing-openings 30.

The boxing has an orificed threaded lug 5 to receive a screw 3, which also traverses a transverse hole in the body 2. Besides this means for securing said boxing to said body, a strap 35 is passed about the handle 1 and 60 fastened to the boxing by screws 36. The boxing is open at the bottom, but provided with slideways 33 to receive a sliding-cover 32 which may have a thumb-notch 34.

The means for reciprocating the plate 8 65 comprises connected elements operated by a shaft 24 within the boxing and a power-driven flexible cable 31. Of these, the numeral 14 denotes an arm projected forwardly from a sleeve 15, the latter rockingly 70 mounted on said screw 11, and this arm has a depending detent 13 which movably and detachably engages the rectangular notch 10 in the plate 8. Another arm 17 of semicircular form also extends from said sleeve 15 75 but in a general opposite direction and has a terminal head 37 provided with an up and down slot 18.

The shaft 24 has a diminished portion traversing the bearing-orifice in the partition 22 and supplied with a disciform extremity 21 having an eccentric crank-pin 20 covered by an anti-friction sleeve 19, and this pin and its sleeve 19 are received within the slot 18 to rotate as well as have a limited 80 sliding movement therein. The other end 26 of said shaft 24 is somewhat enlarged, socketed, and slotted at 27 on one side to detachably receive a head 29 and spline 28 on a helical wire cable 31, which latter may 85 be rapidly rotated by mechanism, not shown, such as an electric motor provided with connecting step-down gearing.

When the cable 31 with the connected shaft 24 and crank-pin 20 are rotated, the pivoted 90 member 14-17 receives continuous rocking motion, imparting to the cutting-plate 8 a rapid reciprocation of short length and very effective in use. The slot 18 in the head 37 of the arm 17 permits the necessary free play 100 to the contacting elements without friction or binding.

All the elements of this device are simple, and readily assembled or disassembled for inspection, cleaning or repairing. The device has a minimum of parts, hence is light and compact, and handy for manipulation, and may be quickly connected to or separated from the power-plant.

Having described my invention, what I 110

claim as new, and desire to secure by Letters Patent, is:

In a device of the character described, in combination, a housing, containing aligned shaft-bearings and having an open longitudinal slideway thereover, a slide closure mounted removably in said slideway, said housing projecting forwardly of said slideway continuing the opening thereof terminally, a shank removably secured on said housing and having a terminally serrated plate cov-

ering the said terminal opening spaced from the housing, a blade mounted between the housing and said serrated plate, a shaft rotatably mounted in said shaft-bearings, and mechanism operatively connected between said shaft and said blade adapted to reciprocate the blade transversely when the shaft is rotated.

Signed at Waterloo, Iowa, this 12th day 20 of May, 1919.

WILLIAM T. ROSE.
